CLAIM

The ornamental design for a fixation clamp, as shown and described.

DESCRIPTION

FIG. 1 is a perspective view of a fixation clamp, in accordance with one embodiment of the present invention.

FIG. 2 is a side view of the fixation clamp shown in FIG. 1; and,

FIG. 3 is a top view of the fixation clamp shown in FIG. 1. Portions of the fixation clamp shown in the drawings in phantom lines constitute no part of the claimed design.

1 Claim, 3 Drawing Sheets
